UNITED STATES PATENT OFFICE.

JOHN J. GHEGAN, OF NEWARK, NEW JERSEY.

FIRE-ALARM BOX.

1,123,122.

Specification of Letters Patent. Patented Dec. 29, 1914.

Application filed August 1, 1913. Serial No. 782,485.

To all whom it may concern:

Be it known that I, JOHN J. GHEGAN, a citizen of the United States of America, and residing at Newark, in the county of Essex and State of New Jersey, have invented a certain new and useful Improvement in Fire-Alarm Boxes, of which the following is a specification.

My invention relates mainly to fire alarm boxes in which there is a make and break signaling means and a sheet of glass which has to be broken before the signal can be given at the central station, and the main object of the invention is to so provide an efficient and simple construction of mechanism, whereby the breaking of the glass will set the signaling means into operation to give at the central station the signal, indicating from which box it comes.

20 A further object of my invention is to so construct this mechanism that a new sheet of glass cannot be put and held in position without setting the signaling means, and that the mechanism cannot be tampered with by any one who has not a key to the box.

25 A further object is to so construct the mechanism that the box can be tested without opening it or resetting it or sending in a regular signal.

30 These objects I attain by the construction which I will now describe.

In the accompanying drawings, Figure 1 is a face view of the box; Fig. 2 is a front elevation with the hinged door removed; Fig. 3 is a front elevation of the control means, after the glass has been broken, and the setting lever about to be released; Fig. 4 is a vertical section on the line 4-4, Fig. 40 1; Figs. 5, 6, 7 and 8 are views of the circuit closing devices in different positions; Fig. 9 is a perspective view of the setting lever, spindle and arms on the latter.

The inclosing box A may be of any suitable construction, such as shown in the drawing, with a hinged front door B, which is adapted to be locked by a suitable key lock C, so that no one without a key can gain access to the mechanism to tamper with it. 45 This door has an opening D for the insertion of a suitable setting key to test the signal. The door has also a relatively large opening E in front of the sheet of glass G, which is to be broken to set free the signaling mechanism and which is mounted as hereinafter described.

F is the setting lever which is mounted upon the spindle 10 of the usual clockwork mechanism, contained within the case H, Figs. 2 and 4 and secured to the insulating base J at the back of the box A. This setting lever F is preferably not rigidly secured to the spindle, but is mounted thereon so as to be free to have a limited independent rotary motion thereon. For this purpose, I provide this lever F, as shown in Fig. 9 with a hub 11, having a pin 12, which when the lever and its hub are slipped into position on the spindle, will lie back of the stop arm 13, which is fixed to the spindle, as indicated in Fig. 5. If now the setting lever be turned clock-wise by hand, as from the position indicated by dotted lines in Fig. 2 to the position shown by full lines therein—the setting position—the spindle 10 will be rotated accordingly to wind up the spring of the clock-work.

The setting lever F is adapted to be held in the "set" position by the glass G, which is held edgewise between a fixed bar 26 mounted on the case H and a lever 20, hinged at 18 to the case. This lever 20 has hinged to its free end at 17, a latch 16 which is guided in a guide piece 23 and has a catch 19 at its upper end to engage over a pin 15 on the setting lever F to hold the latter in the "set" position, as shown in Fig. 2. A light coiled pull spring 22 may be employed, connecting the latch bar 16 with a fixed pin 21 on the casing H, to tend 30 to pull the lever 20 and latch downward when freed from the setting lever F.

I prefer to make the glass plate G in the form of a circular disk and to form in the bar 26 and lever 20 corresponding curved 35 grooves to hold the glass under stress edgewise; when the glass is in position between the bar 26 and lever 20, it holds down the lever F in the set position through the latch bar 16. The strain on the glass plate, being 40 in the direction of its plane, it holds with great strength, and yet when the plate is broken by a blow on its face, there will be an instant release of the lever 20, and the clock mechanism will begin to turn 45 the setting lever F in the direction of the arrow, Fig. 3, drawing up the latch 16 and lever 20. On this latch I form a cam face 24 bearing against a fixed pin 25 on the casing H, so that as the latch 50 bar rises, its nose 19 is pushed off the pin 15, and the lever F is free to continue its 55

movement to the position indicated by dotted lines in Fig. 2, sending, in three or four or as many rounds of its signal as it may be constructed to give under the action 5 of the clock-work. The pin 25 may also serve as a stop to prevent the setting lever from being pulled over too far in getting it to setting position. On putting a new disk 10 of glass in place between the bar 26 and lever 20, the setting lever can be latched and held in set position, but it cannot be so set and held until the glass is put in place. And 15 on the other hand, the glass cannot be held in place until the lever F has been set and the latch 16 engages and holds this lever F. The opening E in the cover is at such a point that when the glass is broken, access 20 cannot be had to the lever F to send in a new signal, or to otherwise tamper with the mechanism, without having the door 18 opened by some one having a proper locking key.

I have heretofore referred to the fact that the setting lever F is not fixedly secured to the spindle 10. The ultimate purpose of 25 this lost motion between the lever F and the spindle is to permit a test signal to be sent in without disturbing the setting for the regular alarm signal. For this purpose the forward end of the spindle 10 is made 30 polygonal and is accessible through the opening D in the cover B of the box, Fig. 1, and a suitable test key is provided to fit on this end of the spindle. By means of the 35 key, the spindle 10 may be turned clockwise without disturbing the lever F and sufficiently to cause the clock work to then turn the break wheel 30, Figs. 5 to 8, contraclockwise one complete revolution before the arm 40 13 on the spindle gets back from the position Fig. 6 to the position, Fig. 5 in contact with the pin 12 on the hub of the lever F, which will then hold the mechanism from further movement until the lever F is in 45 turn released for the sending in of the regular round of signals by the breaking of the glass. In some cases it is desirable that this test signal should not be the same as one round of the regular signal, but merely 50 a momentary breaking or closing of the circuit to see if the circuit is in working order. I therefore provide means, as shown in Figs. 5 to 8 whereby a single breaking or closing of the circuit is given on this test. 55 In passing, I may observe that my invention may be applied to either closed circuit or open circuit work. In the drawings I have shown a closed circuit system, the break wheel 30 being of insulating material and 60 being adapted to act upon the projecting finger 31 of one of a pair of springs 32, and 33, which are mounted on the insulating piece 36 and connected respectively to circuit wires 34 and 35. When the projecting 65 parts of the break wheel 30 bear against

the finger of the spring 32, the latter is pressed into contact with the spring 33 as seen in Fig. 5, and the signaling circuit is closed. When the wheel 30 turns to a position to permit the finger 31 to drop into a 70 notch of the wheel, as seen in Fig. 6, the spring 32 moves out of contact with 33 and the circuit is broken.

On the spindle 10 is mounted an arm 14 (Fig. 9), which is to coöperate with the 75 cammed upper end 44 of a lever 43, pivoted at 42 to a fixed part of the frame. A bent spring 41 tends to press the upper end of this lever 43 toward the arm 14. The lower end of the lever 43 has a pin or equivalent 80 projection 40 in position to press against the projecting end 39 of the spring 31 (Fig. 7) when the upper end of the lever 43 is pressed outwardly by the arm 14.

In Fig. 5, the parts are shown in the normal "set" position, with the end of the arm 14 resting against the upper side of the cam 44 of the lever 43, and with the circuit held closed at 32, 33 by the break wheel 30. If now it is desired to make a 90 test of the line the spindle 10 is turned clockwise by the test key, to an extent which will carry the arm 14 below the cam 44, as seen in Fig. 6. The clockwork then causes the break wheel 30 to turn in the direction 95 of its arrow in this figure, permitting the finger 31 of spring 32 to drop into the first notch as seen in Fig. 6, and to break contact with the spring 33, but before the spring 32 can drop into the next notch, the arm 14 moving in the direction of its arrow, Fig. 6, will have acted upon the cam 44 again, and pushed the lever 43 over so that its pin 40 will have pressed on the end 39 of spring 32 to keep the latter pressed 100 against 33 and the circuit closed until the parts have reached their several positions of rest again shown in Fig. 5.

In Fig. 8, I have shown the positions of the parts after the full round of regular 110 signals has been given on the release of the lever F, and when the latter has been turned back by the clockwork to the position indicated by dotted lines in Fig. 2.

I claim as my invention:

1. A fire alarm box having a make and break signaling means and a hand lever to turn said signaling means to the set position in combination with a glass plate to hold said lever in the set position, but to release it when the glass plate is broken.

2. A fire alarm box, having a make and break signaling means, a hand lever to turn said signaling means to the set position and a latch to hold the lever, in combination with a glass plate to hold said catch and lever but to release them when the glass plate is broken.

3. A fire alarm box, having a make and break signaling means and an operating le-

ver, with a glass plate set under stress edgewise by said lever to hold said means in the set position, whereby on breaking the glass plate, said signaling means will operate.

5 4. A fire alarm box, having a make and break signaling means and a lever to set said means in combination with a glass plate set under stress edgewise to hold said lever in the set position but to release it 10 when the glass plate is broken.

5. A fire alarm box, having a make and break signaling means, a lever to set said means and a latch to hold the lever, in combination with a glass plate set under stress 15 edgewise to hold said latch and lever but to release them when the glass plate is broken.

6. A fire alarm box, having a make and break signaling means, a lever to set said means and a latch to hold the lever, in combination with a fixed bar and a lever carrying the latch, a glass plate set edgewise between the bar and latch lever to hold the latter and the setting lever, but to release them when the glass is broken.

25 7. A fire alarm box, having a make and break signaling means, and a lever to set the same, in combination with a circular glass disk set under stress edgewise by said lever to hold the latter in the set position but to release it when the glass plate is 30 broken.

8. A fire alarm box, having a make and break signaling means and a hand lever to turn said signaling means to the set position, in combination with a glass plate to hold said lever in the set position and means 35

whereby the lever cannot be held set until the glass plate has been put in place.

9. A fire alarm box, having a make and break signaling means and a lever to set the 40 same, in combination with a glass plate to hold said lever in the set position, a locked door for the box having an opening, and a glass back of the opening, the latter being at a point from which the lever is inac- 45 cessible from the outside when the glass is broken.

10. A fire alarm box, having a make and break signaling means including a clock-work and spindle thereon, a lever to set said 50 signaling means and mounted on said spindle with a lost motion, in combination with a glass plate to hold the lever in set position, and a key means to turn the spindle independently of the lever.

55 11. A fire-alarm box, having a make and break signaling means, a lever to set the same and a glass plate to hold the lever in the set position but to release it when the glass is broken, in combination with means 60 for operating the make and break signal mechanism without releasing the set lever and devices for preventing said mechanism from giving a full signal when so operated.

In testimony whereof I have signed my 65 name to this specification, in the presence of two subscribing witnesses.

JOHN J. GHEGAN.
